KITE

Herbert P. Dunne, 1707 NW. 13th St.,
Fort Lauderdale, Fla.

Filed Jan. 28, 1963, Ser. No. 73,346

Term of patent 14 years

(Cl. D34—15)

FIG. 1 is a top plan view of a kite embodying my new design;

FIG. 2 is a bottom view of the kite shown in FIG. 1;

FIG. 3 is a front elevational view of said kite, taken at line 3—3 of FIG. 1;

FIG. 4 is a rear elevational view of said kite, taken at line 4—4 of FIG. 1;

FIG. 5 is a side elevational view of said kite, taken at line 5—5 of FIG. 1;

FIG. 6 is a cross-sectional view thereof, taken along line 6—6 of FIG. 2.

The broken line showings of a tail, string and holder are for illustrative purposes only.

I claim:

The ornamental design for a kite, as shown and described.
